UNITED STATES PATENT OFFICE

2,476,801

KITE

George C. Blazi, Fort Worth, Tex.

Application June 15, 1946, Serial No. 677,032

5 Claims. (Cl. 244—153)

1

This invention relates to kites such as those flown at the end of a string for amusement or for raising instruments.

An object of the invention is to provide a kite construction which is steadier in its flight than those heretofore made.

Another object of the invention is to provide a construction and arrangement which, in addition to the foregoing object, is more appealing in appearance by reason of the unique windmill forming a part thereof.

Another object of the invention is to provide a relatively simple and unique kite construction which is not only more efficient in operation than kites heretofore made, but one which embodies a frame work particularly adaptable to the windmill referred to.

These and other objects will become apparent from the following description of the accompanying drawings, wherein:

Figure 1 is a perspective view of a kite embodying the present invention, and showing the same in flying position.

Figure 2 is a perspective view of the mill forming a part of the kite illustrated in Figure 1.

Figure 3 is an elevational view of the kite frame.

Figure 4 is a perspective view of the kite illustrated in Figure 1, but is shown without the bridle and tail attached.

Figure 5 is an end elevational view of the mill shown in Figure 2 and showing the manner in which the same is rotatably mounted within the kite frame, and

Figure 6 is a broken elevational view of the mill shown at a right angle with respect to Figure 5.

Accordingly, a kite embodying the features of the present invention includes a frame 1, such as shown in Figure 3, and having a face 2 of paper or similar material positioned over and attached to the said frame and secured in the usual manner, such as by folding and pasting the edges of the said paper around the framing string 3. As particularly shown in Figure 3, the frame 1 may be formed of a pair of vertically spaced parallel spines 4 having a pair of spaced and horizontally positioned bows 5 attached thereto. The framing string 3 is attached to the outer ends of the spines 4 and bows 5 so as to define the configuration of the kite. Within the scope of the present invention any configuration may be employed, although the eight-pointed design illustrated is preferred.

The spaced spines 4 and bows 5 define a rectangular opening 6 in the face of the kite and receives therein a mill assembly 7 which is ro-

2

tatably supported upon a horizontal shaft 8 passing through the spines 4 and intermediate the bows 5.

In the illustrated form of the invention, the mill assembly 7 includes a pair of square blocks 9 through which the horizontal shaft 8 is positioned. The blocks 9 are spaced from the spines 4 by means of washer type spacers 10. As particularly shown, in Figures 5 and 6, the mill 7 includes rectangular vanes 11 of stiff sheet material such as cardboard. Each vane 11 is supported by and secured at its ends to corresponding sides of the blocks 9 and have one longitudinal edge even with a corner of the block and having the remainder of the vane 11 projecting outwardly and beyond an adjacent block corner. The width of each vane 11 is such that it will not contact the horizontal portions of the opening 6.

20 By reason of the described construction and arrangement, the mill 7 is allowed to turn freely within the opening 6, and when acted upon by the wind will cause the same to rotate. Although the mill is effective when rotated in either direction, the arrangement of the vanes 11 relative to the block 9 is preferably such that the mill 7 rotates downwardly with respect to the face 2 against which the wind blows.

25 In operation the kite is provided with a suitable bridle 12, a tail bridle 13, and a tail 14 attached to the latter. The kite is flown in the usual manner, but the effect of the mill 7 is such that it prevents the kite from swaying from side to side during flight, and at the same time presents a unique and attractive appearance.

30 What is claimed is:

1. A kite having a frame and a substantially plane surface covering the said frame, an opening in the said surface, and a mill having a horizontal 35 axis substantially parallel with the plane of the said surface and mounted for free rotation within the said opening.

2. A kite comprising in combination a frame, a substantially plane surface covering the said frame, an opening in the said surface defined by portions of the said frame, and a mill mounted for free rotation within the said opening, the axis of the said mill being substantially parallel with the plane of the said surface.

3. A kite comprising in combination, a pair of spaced parallel spines, a pair of spaced parallel bows laterally secured to the said spines, framing strings supported by the said spines and said bows, a surface covering the configuration 55 formed by the said framing string, an opening in

the said surface between the said spines and the said bows, and a mill for rotation within the said opening.

4. A kite comprising in combination, a pair of spaced parallel spines, a pair of spaced parallel bows laterally secured to the said spines, framing strings supported by the said spines and bows, a surface covering the configuration formed by the said framing string, an opening in the said surface between the said spines and the said bows, and a mill having a horizontal axis mounted for free rotation within the said opening.

5. A kite comprising in combination, a pair of spaced parallel spines, a pair of spaced parallel bows laterally secured to the said spines, a surface secured to and supported by the said spines and

the said bows, an opening in the said surface between the said spines and the said bows, and a mill for rotation within the said opening, the axis of the said mill being substantially parallel with the said surface.
